(57) **CLAIM**

The ornamental design for a suspended ceiling grid tee, as shown and described.

DESCRIPTION

FIG. 1 is a perspective fragmentary view of a suspended ceiling grid tee showing a first embodiment of our new design;

FIG. 2 is an end view thereof;

FIG. 3 is a right side fragmentary view thereof, the left side view being a mirror image of this view;

FIG. 4 is a top plan fragmentary view thereof;

FIG. 5 is a bottom plan fragmentary view thereof;

FIG. 6 is an isometric fragmentary view of a second embodiment;

FIG. 7 is an end view thereof;

FIG. 8 is a right side fragmentary view thereof, the left side view being a mirror image of this view;

FIG. 9 is a top plan fragmentary view thereof;

FIG. 10 is a bottom plan fragmentary view thereof;

FIG. 11 is an isometric fragmentary view of a third embodiment;

FIG. 12 is an end view thereof;

FIG. 13 is a right side fragmentary view thereof, the left side view being a mirror image of this view;

FIG. 14 is a top plan fragmentary view thereof;

FIG. 15 is a bottom plan fragmentary view thereof; and,

FIG. 16 is a fragmentary view taken in the plane 16-16 shown in FIG. 11.

The dotted-line showing in the drawings illustrates environment matter and forms no part of the claimed design.
